UNITED STATES PATENT OFFICE.

JOHN H. SHAW, OF NEW HAVEN, CONNECTICUT, ASSIGNOR TO SARGENT & COMPANY, OF NEW HAVEN, CONNECTICUT, A CORPORATION OF CONNECTICUT.

LOCK.

Application filed September 20, 1919. Serial No. 325,060.

To all whom it may concern:

Be it known that I, JOHN H. SHAW, a citizen of the United States, residing in the city and county of New Haven, State of Connecticut, have invented certain new and useful Improvements in Locks, of which the following is a full, clear, and exact description.

This invention relates to locks, and more particularly to rim locks provided with a roller bolt and with means for operating this type of bolt.

The primary object of my invention is to provide novel means for rotating the type of bolt herein disclosed into and out of its locking position.

Another object of my invention is to improve the construction and operation of the type of bolt which is designed to be rocked upon a pair of trunnions into and out of locking engagement with a projecting staple.

Still another object of my invention is to improve the construction, operation and arrangement of parts in the type of lock to which this invention relates.

To these and other ends the invention consists in the novel features and combinations of parts to be hereinafter described and claimed.

30 In the accompanying drawings:

Fig. 1 is a central sectional view taken longitudinally through a lock embodying my invention as applied to a door, a portion of the door and door frame being shown in section.

Fig. 2 is an inside view of the lock shown in Fig. 1, the cap plate being removed to disclose the interior of the lock, the mechanism being shown in its locked position.

40 Fig. 3 is a view similar to Fig. 2, but showing the parts in their unlocked position.

Fig. 4 is a sectional view taken on the line 4—4 of Fig. 1 looking in the direction of the arrows.

45 Fig. 5 is a sectional view on the line 5—5 of Fig. 1 looking in the direction of the arrows.

Fig. 6 is a plan view of part of the operating mechanism removed from the lock 50 casing; and

Fig. 7 is a plan view of the opposite side of the mechanism shown in Fig. 6.

In the drawings, I have shown a rim lock casing 10 having the mechanism involving

my invention mounted therein. The casing 55 10 is shown mounted upon the door 11, so that a portion of this lock casing extends beyond the edge of the door some distance, so that this projecting portion will cover a jam staple or strike 12 secured to the door 60 frame 13. The jam staple 12 is preferably provided with a base portion 14, which is L-shaped in cross-section, as shown in Fig. 1, and this base portion is preferably mortised in the door frame 13, as shown. The 65 lock casing 10 is preferably provided with an outwardly flaring portion 15 surrounding the same, and in order that this casing may be firmly secured to the door 11, a number of screw-holes 16 are formed through this 70 flaring portion of the casing, in which securing screws 17 are mounted.

Inside of the casing 10 and adjacent the forward end of the same, I have formed the spaced bearings 18, and these bearings are 75 adapted to rotatably receive the trunnions 19 projecting from the opposite ends of the bolt 20. I prefer to designate this bolt 20 as a roller bolt, since it is somewhat cylindrical in appearance and is mounted to roll or rock 80 upon its trunnions. In order that this bolt may operatively engage the projecting staple 12, I have formed intermediate of the ends thereof a curved finger 21 adapted to be hooked under the staple 12 when the roller 85 bolt is rocked to its locked position. In order that the portions of the bolt 20 lying to each side of the finger 21 will clear the parallel legs of the staple 12, when the roller bolt is swung to its locked position, I have 90 cut away this bolt, as indicated at 22. The body portion of this bolt is hollowed out or is given a shell-like configuration, as shown in Fig. 1, in order that the interior thereof will clear the outer face of the staple as the 95 bolt is rocked into locking engagement with this staple.

I have provided the following mechanism operated by a thumb-turned hub for rocking the roller bolt 20 into and out of locking engagement with the staple 12. In the outer face of the casing 10 is preferably rotatably mounted a thumb-turned hub 23, the same being provided with a shank 24, which extends into the casing 10, and upon the inner 100 end of this shank is rigidly secured the wing member 25. In order that the thumb-turned hub will normally remain in the position

shown in Figs. 1 and 2, so that the oppositely projecting wings upon the member 25 will be out of engagement with the sliding bar which they operate, I provide the U-shaped spring 26 having parallel legs, as shown in Fig. 2, which resiliently engage the flattened faces of the elliptical plate 27 secured to the shank 24. The U-shaped spring 26 preferably has a loop formed at one end thereof, 10 which loop is secured to the inner face of the casing 10 by means of a washer and cooperating screw 28, as clearly shown in Figs. 1 and 2, and in order to retain the parallel legs of the member 26 out of engagement with 15 the winged member 25, a washer or disk 29 is preferably mounted between the elements 25 and 27. The thumb-turned hub 23 is provided to operate the sliding bar 30, which extends longitudinally within the casing 10 20 and is mounted to one side of the hub 23, as shown in Figs. 2 and 3. This sliding bar is provided with the usual talons 31 adapted to be operatively engaged by either wing of the member 25 to thereby impart a sliding 25 movement to this bar. In order that the bar 30 may be guided as it is operated back and forth, I have provided the lugs 32 formed upon the inner face of the casing, as shown in Fig. 1, and these lugs are received 30 between the spaced projections 33 and 34 formed upon the under face of the bar 30 adjacent the forward and rear ends respectively of the same. Upon the forward face of the sliding bar 30 is mounted a swinging 35 tumbler 35, the same being pivotally mounted upon the bar by means of a stud or pin 36. This tumbler extends longitudinally of the sliding bar and is provided with a projection 37 positioned between the spaced 40 talons 31, and adjacent the free end of this tumbler is formed a lug 38 adapted to cooperate with the post 39 which extends upwardly through the relatively long slot 40 formed in the bar 30. In order that the 45 tumbler 35 will normally be retained in locking engagement with the post 39, I provide the spring 41, one end of which reacts against the lug 42 formed upon the sliding bar. Adjacent the forward end of the sliding bar 30 is formed a notch 43, which is 50 adapted to receive one end of the link 44. The other end of this link extends into a similar notch 46 formed in one face of the roller bolt 20. One end of this link 44 is 55 operatively connected to the sliding bar by a pin 47, while the opposite end of this link is operatively connected to the roller bolt in a similar manner.

From the construction so far described, it 60 will be seen that whenever the thumb-turned hub is turned in the proper direction, one of the wings upon the element 25 will be introduced between the talons 31 to engage the projection 37 to force the same in a rear- 65 ward direction sufficiently to disengage the

tumbler from the fixed post 39, whereupon the wing will engage one of the talons 31 to operate the sliding bar and thereby operate the roller bolt 20.

In order that my locking mechanism may 70 be operated from the outside of the door upon which it is mounted, I provide a cylinder or any other preferred type of lock 48 having the escutcheon plate 49. This lock is preferably secured in a hole formed 75 through the door by means of a plate 50 clamped against the inner face of the door by the screws 51 threaded in the lugs 52 provided upon the opposite sides of the lock 48. This lock 48 is preferably provided 80 with a key barrel (not shown) to the inner end of which is secured the key rod 53 upon which is operatively mounted a rollback 54, which rollback is adapted to cooperate with the talons 31 and the projection 37 in the 85 manner above pointed out to operate the sliding bar. The interior of the casing 10 is preferably closed by a cap plate 55, which is secured in place by screws 56 threaded into the projecting posts 57. 90

From the above description, when read in connection with the drawings, it will be seen that I have provided a very strong and durable lock, the locking mechanism of which may be operated either by means of 95 a key inserted from the outside of the door or by a thumb-turned hub upon the inside of the door, and it will also be seen that the link 44 provides a very satisfactory means for imparting a rocking movement to the 100 roller bolt 20 by moving the sliding bar 30 in one direction or the other.

It will be apparent that various changes may be made in the particular embodiment 105 of my invention herein disclosed without departing from the scope of my invention as defined in the annexed claims.

What I claim is:

1. In a lock of the character described, a lock case, one face of which is adapted to be applied to a door, a bolt, trunnions mounting in said bolt in the case on an axis parallel to the said face, a slide, a link pivoted to the slide and to the bolt to swing upon axes parallel to the first mentioned axis, the connection between said link and bolt being disposed upon the side of the bolt axis opposite the said face of the lock case, and means for operating the slide. 110

2. In a lock of the character described, a lock case, one face of which is adapted to be applied to a door, a bolt, trunnions mounting in said bolt in the case on an axis parallel to the said face, a slide, a link pivoted to the slide and to the bolt to swing upon axes parallel to the first mentioned axis, the connection between said link and bolt being disposed upon the side of the bolt axis opposite the said face of the lock case, a swinging tumbler for retaining the slide in the 115 120 125 130

desired position and means for operating the slide.

3. In a rim lock, a casing, a roller bolt rotatably mounted within the casing and provided with a curved locking finger, an operating member slidably mounted within the casing, and a link connecting said member to the bolt, the connection between said link and bolt being disposed on the side of the bolt axis opposite the finger.

4. In a lock of the character described, a lock case, one face of which is adapted to be applied to a door, a roller bolt rotatably mounted in the casing on an axis parallel to the said face, an operating slide mounted in the case, and means connecting said slide to the bolt upon the side of its axis opposite the said face of the lock case.

5. In a rim lock, a casing, a roller bolt rotatably mounted within the casing and provided with a curved locking finger, an operating member slidably mounted within the casing, and a link pivoted to said member and to the bolt, the connection between

said link and bolt being on the side of the bolt axis opposite the finger.

6. In a lock of the character described, a lock case, one face of which is adapted to be applied to a door, a roller bolt rotatably mounted in the casing on an axis parallel to the said face, an operating slide mounted in the case, and a link connecting said slide to the bolt upon the side of its axis opposite the said face of the lock case.

7. In combination, a strike plate having a projecting staple, a lock case adapted to be applied to a door and having an opening to receive said staple, a roller bolt swingably mounted in said casing and having a curved finger adapted to engage the staple, an operating slide to actuate said bolt and a link connecting said slide to the bolt, said link passing above said staple when the bolt is moved to locked position.

In witness whereof, I have hereunto set my hand on the 17th day of September, 1919.

JOHN H. SHAW.
